UNITED STATES PATENT OFFICE.

GEORGE F. RAUCH, OF PUKWANA, SOUTH DAKOTA.

TIME-OPERATED CIRCUIT CLOSER.

Application filed May 19, 1925. Serial No. 31,327.

This invention relates to circuit closers and particularly to a time operated circuit closing mechanism for controlling a plurality of associated or independent electric circuits and for closing said circuit at predetermined time intervals.

An object of the invention resides in providing a time operated circuit closer, including a cylinder suitably mounted for rotative movement, adjacent a plurality of circuit closing members or mechanism, so that predetermined portions of the cylinders are adapted for controlling the operation of said mechanism, in effecting the closing and opening of the circuit controlled thereby.

Another object of the invention resides in providing a mounting for the circuit closing mechanism and the controlling means therefore, wherein a pair of plate members arranged in spaced parallel relation are connected by a bar member, positioned in spaced parallel relation to the periphery of a cylinder formed in a predetermined manner for controlling the operation of the circuit closing mechanism carried by the bar member, while a clock mechanism is mounted on one of the plate members and carries a bearing for one end of the cylinder, so that driving mechanism can be suitably mounted on the clock mechanism and shaft for the cylinder and maintained in constant driving connection.

The invention further includes a circuit closing mechanism having a pair of elements mounted in spaced relation in a bar member and formed with laterally extending ends, one of said ends pivotally supporting a special contact member having a foot for normally engaging the periphery of an operating cylinder, while the other end is formed for cooperation with the lateral end of the other rod member for circuit closing cooperation therewith.

The invention comprehends other objects and improvements in the details of construction and arrangement of the parts as are more particularly pointed out in the following detailed description and in the claims directed to a preferred form of the invention, it being understood, however, that various changes in the size, shape, and arrangement of these parts may be made, without departing from the spirit or scope of the invention as set forth herein.

In the drawing, forming a part of this application:

Figure 1 is a vertical longitudinal section through the device, showing portions in elevation.

Figure 2 is a horizontal sectional view, taken on the line 2—2 of Figure 1.

Figure 3 is an enlarged detail transverse section through a portion of the cylinder and bar member showing the detailed construction of one of the circuit closing mechanisms.

Figure 4 is a perspective view of the movable circuit closing arm or switch member.

Figure 5 is a detail perspective view of one of the rod members mounted in the bar member adapted to pivotally mount the switch member.

Figure 6 is a vertical sectional view, longitudinally of the cylinder and shaft supporting the same showing parts in elevation and illustrating particularly an additional control element for one of the switch mechanisms.

Figure 7 is a plan view of the construction shown in Figure 6 with the top removed and portions shown in section.

Figure 8 is a vertical transverse sectional view, further illustrating the construction shown in Figure 6.

A cabinet is indicated generally at 1, which includes a base 2, a front wall 3, a back wall 4, and a top 5, suitably assembled together. A partition wall or plate member 6 is mounted within the cabinet 1 in spaced parallel relation between the front and back walls 3 and 4 respectively, as clearly illustrated in Figure 1 of the drawings. At the upper end portions and slightly below the top 5 of the cabinet, the partition 6 and the rear wall or plate member 4 are connected by a bar member 7 for the purpose of supporting circuit closing mechanism of a character to be hereinafter described. Partitions 6 or plate member 100 mounts a clock mechanism of any desired form or character well known in the art, which is indicated by the numeral 8, by means of a pair of brackets 9. The concentric shaft for the minute and hour hands 105 of the clock mechanism 8 are indicated at 10 and 11 respectively, and carry at their outer ends the hands 12 for cooperation with

the usual dial 13 mounted within the opening formed in the front wall of the cabinet, and covered by the glass plate 14.

A roller bearing 15 is mounted on the 5 clock mechanism 8 at 16 and rotatably mounts one end of the shaft 17 which extends through an opening 18 in the plate member 6, and has a ball bearing mounting at 19, in the rear plate member 4, for rotatably supporting the cylinder 20, in proximity to the bar member 7, as illustrated in Figure 1 of the drawings. A spur gear 21 is mounted on the end portion of the shaft 17, adjacent the bearing 15 and intermeshes with a gear 22, mounted on the outer shaft 11 of the clutch mechanism 8. A plurality of circuit closing mechanisms are mounted transversely of the bar member 7, in spaced parallel relation, as illustrated 15 in Figures 1 and 2, one of such mechanisms being shown in detail in Figure 3. Each circuit closing mechanism includes a pair of insulating sleeves 23, which are mounted in the bar members 7 and which carry rod members 24 and 25 respectively therein. The ends of these rods 24 and 25 project beyond the ends of the sleeves 23 and are threaded at the upper end, as at 26, while their lower ends are provided with lateral 25 projecting portions 27 and 28 respectively, on the respective rods 24 and 25. The rod 24 forms a stationary contact member, while the rod 25 forms a support for the movable contact member of the circuit closing mechanism, and for this purpose carries a shoulder portion 29 while the end of the lateral extension 28 is threaded, as indicated at 30, for receiving a nut 31, adapted to pivotally retain the switch member 32 thereon. The switch member 32 is provided with a lateral projection 23, adapted to engage and ride on the surface of the cylinders 20. One end of the switch member 32 is provided with a notched portion 34, adapted to 40 fit the laterally extending ends 27 of the stationary contact rod 24. The opposite end of the switch member 32 is provided with an extension 35, on which rides a curved leaf spring 36, which is anchored at one 45 end, as at 37 on the bar member 7. The spring normally operates to move the switch member 22 to engage the stationary contact for the purpose of closing the circuit connected with the rods 24 and 25. The 50 cylinder operates the switch member through engagement with the laterally extending arm 33, for retaining the switch member in disengaged relation with the stationary contact and holding the circuit open. However, 55 when it is desired to close the circuit controlled by the cylinder, the cylinder is provided at the desired point in the zone of rotation of a particular contact mechanism with recesses 38, which will permit the 60 operation of the switch member by the spring 65

36, to circuit closing position, in the manner as clearly illustrated in Figure 3 of the drawing. The zones of the cylinder 20 controlling the operation of each independent circuit closing mechanism may be formed 70 in any desired predetermined manner, for controlling and permitting the operation of the mechanism to close the circuit controlled thereby at predetermined time intervals as may be desired. It is to be understood that 75 while the cylinder is shown with recessed portions, any other desired construction of the cylinder may be used for producing the same controlling action of the contact mechanism within the scope of this invention. 80

In Figures 6, 7, and 8, a construction is illustrated, which is similar in all respects to that shown in Figures 1 to 5, with the additional feature of a contact mechanism 85 controlled by the cylinder 20, which is provided on the switch arm 32' with a laterally projecting pin 40, which extends beyond the rear end of the cylinder, as shown in Figures 6 and 7 for cooperation with the arcuate flange 41 on the gear wheels 42 rotatably mounted on the stub shaft 43 and driven by the small pinion 44 on the shaft mounting the cylinder 20, the pinion 44 and the gear 42 are such as to provide a special timed 90 relation between the rotation thereof, so that in the operation of the clock mechanism, the cylinder 20 will rotate seven revolutions to one of the gear 42. In this way, the flange 41 will ride over top of the pin 40 and the switch lever 32' every seventh day, and prevent the operation of the switch arm 32' to close the circuit controlled thereby when the recess in the cylinder passes under the lateral finger projecting from the switch arm. This construction is adapted for use in sounding alarms or similar signals for week days and where it is desired not to have this signal or alarm to be sounded on Sundays. 100

A construction of this character is particularly adapted for use in factories, cities, towns or the like, where gongs, bells, whistles, machines or other apparatus is desired to be operated at predetermined time intervals for the automatic control of the operation of these several elements. 110

What is claimed is:

1. A circuit closing mechanism, comprising a supporting structure, a bar member mounted on said supporting structure, a plurality of circuit closing mechanisms mounted in spaced relation on said bar member, each of said mechanisms including a pair of insulating sleeves mounted in spaced relation in the bar member, rods mounted in said insulating sleeves, said rods having lateral projections from corresponding ends thereof, a switch member pivotally mounted on the lateral extension of one of 120
- 125
- 130

said rods and formed for engagement with the lateral extension of the other rod, said switch member having a lateral extension therefrom, and resilient means mounted on 5 the bar member normally engaging the switch member to operate said switch member to engage the lateral extension of the bar member.

2. A circuit closer, comprising a bar member, a pair of rods mounted in the bar member in spaced parallel relation and in-

sulated from each other, each of said rods having lateral extensions on corresponding ends, a switch member pivotally mounted on the lateral extension of one rod and formed for engagement with the lateral extension on the other rod, and resilient means for normally operating said switch member in one direction. 15

In testimony whereof I affix my signature.

GEORGE F. RAUCH.
